UNITED STATES PATENT OFFICE.

FRANK A. SMITH, OF OCONTO, WISCONSIN.

CARBURETER.

SPECIFICATION forming part of Letters Patent No. 607,888, dated July 26, 1898.

Application filed September 27, 1897. Serial No. 653,225. (No model.)

To all whom it may concern:

Be it known that I, FRANK A. SMITH, of Oconto, in the county of Oconto and State of Wisconsin, have invented a new and useful Improvement in Apparatus for Making Gas, of which the following is a description, reference being had to the accompanying drawings, which are a part of this specification.

My invention has relation to apparatus for making gas; and it pertains more especially to that class of gas apparatus which is intended to be set up for use in dwellings, hotels, office-buildings, and the like in order that gas may be manufactured and supplied for a particular premises.

The primary object had in view is to secure a uniform pressure of the gas in the distributing gas-holder, this being accomplished by forcing liquid gas from the storage-tank to the generator and providing means for raising the initial gas-holder, so that a vacuum is formed in said holder and the vapor gas thereby admitted therein from the generator, and also providing means for causing a subsequent descent of the initial gas-holder by gravity, so as to force the vapor gas into the distributing gas-holder, ball-valve mechanism in the distributing gas-holder compelling uniform pressure of the gas.

An incidental object contemplated is the automatic regulation of the quantity of gas admitted to the distributing gas-holder.

A still further object resides in a novel and improved form of valve mechanism for the forcing-pump.

With the above and other incidental objects in view the invention consists of the devices and parts or their equivalents, as hereinafter more fully set forth.

In the accompanying drawings, Figure 1 is a side elevation of the complete apparatus, showing parts in section. Fig. 2 is a plan view. Fig. 3 is a detail view of the pump and valve mechanism. Fig. 4 is a sectional view through the valve of Fig. 3. Fig. 5 is a sectional view of the generator mechanism, and Fig. 6 is a detail view of the perforated inlet pipe.

Referring to the drawings, the numeral 7 indicates a main storage-tank for containing gasoline or its equivalent.

The numeral 8 indicates a water-tank, which

is partially filled with water, and 9 the distributing gas-holder, consisting, as usual, of an open-bottom cylinder inverted into the tank. The gas-holder is advisably provided at its lower end, upon its outer side, with rollers 10, which are adapted to bear against the inner side of the tank 8, and the tank 8 may also be provided at its upper end with similar rollers 11, which bear against the holder. These rollers serve to maintain the holder in true upright position and also facilitate the movement up and down of said holder. Extending through the lower end of the tank 8 and up into the gas-holder 9 is a gas-distributing pipe 12. This pipe after leaving the tank is extended so as to conduct the gas to the different rooms or apartments to be lighted.

The numeral 13 indicates an initial gas-holder which fits and is adapted to reciprocate in a water-tank 14, partially filled with water. The lower end of this gas-holder has projecting outwardly and upwardly therefrom an annular flange 15, which bears at its outer upper edge against the inner side of the tank 14 and serves to maintain the gas-holder in true position within the tank.

The cylinder of the pump mechanism is indicated by the numeral 16. Within this cylinder is a piston 17, which is provided with an upwardly-extending piston-rod 18, which rod extends through the top of the pump. Projecting upwardly from the top of the gas-holder 13 is an arm 19, which forms a fulcrum for a rocking lever 20, one end of said rocking lever being pivotally connected to the upper end of the piston-rod and the opposite end of said lever being pivotally connected to an arm 21. The lower end of this arm 21 is pivotally connected to an upright 22.

An air-pipe 23 extends from the upper end of the pump-cylinder to the upper end of the gasoline-storage pipe 7. The passage of the air through this pipe is controlled by means of a flap-valve 24. Extending into the upper end of the pump-cylinder also is a short air-intake pipe 25, which has connected to its outer end a coupling 26, forming a valve-chamber for a flap-valve 27. Entering the lower end of the pump-cylinder is a water-inlet pipe 28, which leads from the city water-works or from any suitable source of water-supply, so as to conduct water under pres-

sure to the lower end of the pump-cylinder in the space beneath the piston thereof. A water outlet or discharge pipe 29 leads from the lower end of the pump-cylinder. In each 5 of these pipes is mounted a crank-shaft. The crank-shaft of the inlet-pipe is designated by the numeral 30 and that of the outlet-pipe by the numeral 31. The cranks of these respective shafts extend in opposite directions. 10 Within the inlet-pipe is formed a valve-seat 32 and within the outlet-pipe a similar seat 33. Against these seats are adapted to work, respectively, inlet and outlet valves 34 and 35. These valves are provided, respectively, 15 with projecting stems 36 and 37, said stems being connected to the respective cranks of the shafts 30 and 31. To the outer exterior ends of the shafts 30 and 31 are connected, respectively, crank-arms 38 and 39. 20 Connected to and extending from the pump-cylinder, near the lower end thereof, is a bracket or arm 40. Pivoted on this bracket at the point 41 is a tumbling-bob consisting of an upright arm 42, provided at its upper 25 end with a weight 43 and an intersecting cross-arm 44. To one end of the intersecting arm is connected a rod 45. This rod extends upwardly a desired distance above the top of the pump-cylinder and has mounted thereon, 30 at desired distances apart, adjustable contact-collars 46 46'. Connected to the crank-arms 38 and 39, which are connected, respectively, to the outer ends of the shafts 30 and 31, are other rods 47 47', said rods passing through 35 opposite ends of the intersecting arm 44. Rod 47 has mounted thereon above and below the end of the intersecting arm through which it passes adjustable contact-collars 48 48, and rod 47' has mounted thereon at corresponding 40 points similar adjustable contact-collars 48' 48'.

On the upper end of the piston-rod 18 is 45 adjustably mounted an arm 49. The rod 45 passes freely through an opening in the end of this arm, said end through which the rod passes being located between the adjustable 50 collars 46 and 46'.

The numeral 50 indicates the gas-generator, 55 consisting of a cylindrical tank, which is partially filled with gasolene. A pipe 51 extends from the lower end of the gasolene-storage tank 7 and connects with a supplemental chamber 52, projecting laterally from the gas-generator. This pipe extends into said supplemental chamber and connects with an L-coupling 53. One end of the L-coupling is 60 extended into the pipe 51 for a short distance to form a valve-seat 54. Against this seat is adapted to work a valve 55, said valve provided with an inwardly-projecting spring-actuated valve-stem 55', which extends through the inner end of the L-coupling and connects with a short arm 56, extending from a lever 57. Said lever is pivoted to a projecting lug 58, and at the extremity of said lever is connected a float 59.

The numeral 60 indicates an air-intake

pipe which at its outer end communicates with the external atmosphere, and its lower end extends into the generator-tank and connects with a perforated ring or annulus 61, which is located in the lower part of the tank and is adapted to be submerged by the gasolene contained therein. To the outer upper end of the pipe 60 is connected a coupling 52, 70 75 forming a valve-chamber for a flap-valve 63. From the top of the gas-generator projects a pipe 64, which pipe is extended to and into the water-tank 14 and thence upwardly into the gas-holder 13 for discharging into the 80 space of the gas-holder above the water-line.

The numeral 65 indicates a pipe which connects the gas-holders 9 and 13. One end of this pipe is located in the space of the gas-holder 13 above the water-line, and is then 85 extended downwardly and outwardly through the water-tank 14, thence to and through the water-tank 8, and its discharging end is formed or provided with an elongated conical portion 66, the upper extremity of said conical discharging portion extending a distance into the gas-holder 9 at a point just above the upper edge of the water-tank 8. To the end of the pipe 65 which is located in the gas-holder 13 is connected a coupling 67, which forms a 90 95 valve-chamber for a flap-valve 68. Extending through the upper end of this conical portion and into said conical portion for a desired distance is a rod 69. The lower end of this rod, within the conical portion, is formed 100 with a ball-valve or enlargement 70. The rod is made adjustable by threading its upper end and passing said threaded end through an opening 71 in the top of the gas-holder 9. Nuts 72 72 engage the threads of the rod and 105 are adapted to be turned up against opposite sides of the top of the gas-holder, as clearly shown in Fig. 1, in order to adjust and hold the rod to adjusted position. An opening 73 is provided in the top of the gas-holder 9, 110 which opening is covered by means of a screw-cap 74. By removing this screw-cap access can be readily obtained to the interior for the purpose of adjusting the inner nut 72.

The operation of my improved apparatus 115 is as follows: The liquid gasolene is free to enter the gas-generator 50 whenever the valve 55 is away from its seat and there is a pressure on the surface of the gasolene within the gasolene-tank. The valve is moved away 120 from its seat whenever the float falls to such an extent by the lowering of the level of the gasolene in the generator as to act on the rod of said valve and force the valve away from its seat against the pressure of the coiled 125 spring. As soon as the generator fills to a certain height the float is again raised to such an extent as to force the valve against its seat and stop further inflow of the gasolene. It will be understood that the coiled 130 spring is not absolutely necessary, as the float itself would be sufficient to force the valve to its seat.

In the open position of the water-inlet valve

34 (shown in Fig. 4 of the drawings) the water under pressure is free to pass into the pump-cylinder 16 into the space beneath the piston 17. The pressure of the water against said 5 piston will cause the piston to rise, and with this upward movement the lever 20 will be acted upon. This lever through the connecting-arm 19 will raise the gas-holder 13. With the raising of said gas-holder a vacuum is 10 formed therein and a suction is created through the pipe 60, which opens the flap-valve 63 and draws the external air through said pipe into the annulus or ring 61 and thence out through the perforations of said 15 ring. The air thus issuing through the perforations passes into and through the gasoline and is thoroughly impregnated therewith, becoming a gaseous vapor, which enters and fills the space of the gas-holder 13 above 20 the water-line, the water forming a seal against the escape of the gas. After the piston-rod 18 has moved a certain distance upwardly the contact-arm 49 thereof will contact with the contact-collar 46 and cause an 25 up movement of the rod 45. Figs. 1 and 3 show the arm in contact with the collar 46. This rod 45 will act on the end of the cross-arm 44 and cause a tilting of the tumbling-bob mechanism in a direction to the right of 30 Fig. 3. Fig. 3 shows the arm 42 moved as far as a vertical position. The moment the upright arm 42 is tilted past this vertical position the weight 43 completes the movement of the tumbling-bob. There is a slight lost 35 motion in the cross-arm 44 until the ends thereof contact with the contact-collars 48 and 48'. Contact with the collar 48 will cause a turning of the crank-shaft 30, so as to close the inlet-valve 34, and contact with 40 the collar 48' will cause a turning of the crank-shaft 31, so as to cause an opening of the outlet-valve. The water is now free to 45 pass out of the pump-cylinder. In further explanation it will be understood that if gas is permitted to pass out of the pipe 12 the gas-holder 9 will necessarily descend so as to move the ball-valve 70 away from the contracted portion of the conical discharge 66. This will at once permit gas in the holder 13 50 to flow through the pipe 65 into the gas-holder 9, so as to fill said gas-holder with a quantity of gas equal to that withdrawn therefrom, and this operation takes place before any operation whatever of the pump-valve mechanism 55 occurs—that is to say, the gas-holder 13 descends a certain distance in order to force the gas into the holder 9, and after said holder 13 has descended this certain distance the arm 49 will contact with collar 48' and throw 60 the tumbling-bob mechanism in a direction to open the inlet and close the outlet valve, when of course the operation first explained again takes place.

It will be understood that if, after the outlet-valve is open and the water beneath the piston flows out through the outlet-valve, the gas is turned off or is not being used, then the

piston will remain at its adjusted position. It will also be understood that on the lowering of the gas-holder 13 the pressure through 70 the pipe 64 causes a closing of the flap-valve 63, so that no escape can occur through the pipe 60, while at the same time the flap-valve 67 is opened and the gas forced into the pipe 65 and discharged through the conical portion 75 66 of said pipe. It will be evident that whenever the piston 17 ascends the air in the cylinder above said piston is forced through the pipe 23 into the tank 7, so as to act on the upper surface of the gasoline contained in said 80 tank and force said gasoline through the pipe 51 into the generator 50. When the piston ascends, the flap-valve 24 is opened and the valve 27 closed, while on the down movement of the piston the reverse takes place—that is 85 to say, the flap-valve 24 closes and the valve 27 is opened.

The rod 69 and the ball-valve 70 on the lower end thereof are not only for the purpose of governing the amount of gas entering 90 the holder 9, but are also for the purpose of controlling the distance the gas-holder 9 can be raised vertically—that is to say, they prevent said gas-holder from being raised to such a vertical height as to bring its lower edge 95 above the water-line and thereby allow the escape of the gas. The rod is so adjusted that after the gas-holder has been raised to such a height as to bring its lower edge nearly to the surface of the water the valve 70 will 100 have been raised sufficiently high to bring it into the contracted portion of the conical discharge and thereby close the piston against further flow of the gas into the gas-holder.

From the above description it will be seen 105 that in my improved apparatus the gas is forced from the initial gas-holder 13 into the distributing gas-holder 9 by means of the descent by gravity of the gas-holder 13, while said gas-holder 13 is raised by means of a 110 pump. The ball-valve 70 necessarily produces an even feed of the gas into the holder 9, and consequently an even pressure of the gas in said holder. In other forms of apparatuses the gas is forced from the initial gas- 115 holder into the terminal or distributing gas-holder by means of pump mechanism, which is found objectionable in that an uneven pressure is produced. Attention is also called to the fact that all of the parts of my apparatus need not necessarily be located in one 120 building, but that the gasoline-storage tank 7 may be located at one place, the water-tank 8 and the gas-holder 9 fitting therein at another place, while the water-tank 14 and gas-holder 13, together with the generator 15, may be located at still another point. In many 125 forms of apparatuses all of the different portions thereof are required to be located at one point.

What I claim as my invention is—

1. In an apparatus for making gas, the combination, of initial and terminal gas-holders, water-tanks in which said holders are fitted

and move, a source of gas-supply, a pipe leading therefrom and into the initial gas-holder, and adapted to permit free flow therethrough into the initial gas-holder on the up movement of said initial gas-holder, a pipe extending from the initial gas-holder to and into the terminal gas-holder to convey gas to the latter, a distributing-pipe leading from the terminal gas-holder, pump mechanism, mechanism between the piston-rod of the pump and the initial gas-holder, whereby the upward movement of the piston operates to produce an up movement of the initial gas-holder, and for causing the initial gas-holder to descend by gravity as the water is discharged beneath the piston and when gas is taken from the distributing gas-holder, the up movement of the initial gas-holder producing a vacuum therein, and a suction from the source of supply into said holder, and the descent of said holder forcing the gas through the pipe leading to the terminal gas-holder.

2. In an apparatus for making gas, the combination, of initial and terminal gas-holders, water-tanks in which said holders are fitted and move, a source of gas-supply, a pipe leading therefrom and into the initial gas-holder, and adapted to permit free flow therethrough into the initial gas-holder on the up movement of said initial gas-holder, a pipe extending from the initial gas-holder to and into the terminal gas-holder to convey gas to the latter, a distributing-pipe leading from the terminal gas-holder, a pump, valve-controlled inlet and outlet pipes leading to and from the pump-cylinder, respectively, mechanism between the projecting end of the piston-rod of the pump and the initial gas-holder, whereby, when the piston is raised, said gas-holder is raised therewith, and when the gas-holder descends, the piston is lowered therewith, and mechanism for controlling the valves of the inlet and outlet pipes of the pump, whereby, after the piston of the pump has moved in one direction, a certain distance, the inlet-valve will be closed and the outlet-valve opened, and vice versa, when the piston is moved a certain distance in the opposite direction, the outlet-valve will be closed and the inlet-valve opened.

3. In an apparatus for making gas, the combination, of initial and terminal gas-holders, water-tanks in which said holders are fitted and move, a source of gas-supply, a pipe leading therefrom and into the initial gas-holder, and adapted to permit free flow therethrough into the initial gas-holder on the up movement of said initial gas-holder, a pipe extending from the initial gas-holder to and into the terminal gas-holder, a distributing-pipe leading from the terminal gas-holder, a pump, valve-controlled inlet and outlet pipes leading to and from the pump-cylinder, respectively, mechanism between the projecting end of the piston-rod of the pump and the initial gas-holder, whereby, when the piston is raised said gas-holder is raised therewith, and when

the gas-holder descends the piston is caused to descend therewith, tumbling-bob mechanism, and mechanism carried by the piston-rod for controlling the tumbling-bob mechanism, whereby, after the piston of the pump has moved in one direction a certain distance, the tumbling-bob will be tilted in one direction so as to close the inlet-valve and open the outlet-valve, and vice versa, when the piston is moved a certain distance in the opposite direction, the tumbling-bob is tilted in a reverse direction to that in which it was first tilted, so as to close the outlet-valve and open the inlet-valve.

4. The combination with the initial and terminal gas-holders of a pump, a contact-arm extending from the projecting end of the piston-rod of the pump, inlet and outlet pipes leading to and from the pump-cylinder, respectively, valves for controlling said pipes, tumbling-bob mechanism, consisting of an arm pivoted to the pump-cylinder, said arm formed or provided with an intersecting cross-arm, a rod connected to one end of the cross-arm, said rod passing freely through the contact-arm of the piston-rod, collars on the rod located, respectively, above and below the contact-arm, rods passing freely through the ends of the cross-arm of the tumbling-bob mechanism, collars mounted on the respective rods above and below the cross-arm, shafts extending into the inlet and outlet pipes, and provided therein, respectively, with opposite cranks to which the valve-rods of the inlet and outlet valves are connected, and crank-arms at the outer ends of said shafts, to which crank-arms the ends of the last-referred-to rods are connected.

5. In an apparatus for making gas, the combination of initial and terminal gas-holders, water-tanks in which said holders are fitted and move, a source of gas-supply, a pipe leading therefrom and into the initial gas-holder, and adapted to permit free flow therethrough into the initial gas-holder on the up movement of said gas-holder, a pipe extending from the initial gas-holder to and into the terminal gas-holder, a distributing-pipe leading from the terminal gas-holder, pump mechanism, a rocking lever connected to the initial gas-holder, and also pivotally connected at one end to the piston-rod of the pump, and having a pivot connection at its opposite end, connections whereby the upward pressure against the piston causes an up movement of the initial gas-holder, and means for causing the initial gas-holder to descend by gravity as the water is discharged beneath the piston and when gas is taken from the distributing gas-holder, the up movement of the initial gas-holder producing a vacuum therein, and a suction from the source of supply into said holder, and the descent of said holder forcing the gas through the pipe leading to the terminal gas-holder.

6. In an apparatus for making gas, the combination, of initial and terminal gas-holders,

water-tanks in which said holders are fitted and move, a source of gas-supply, a generator, a pipe connecting the source of supply with the generator, a pipe leading from the 5 generator to the initial gas-holder, and adapted to permit free flow therethrough into the initial gas-holder on the up movement of said initial gas-holder, a pipe extending from the initial gas-holder to and into the terminal gas-holder, a distributing-pipe leading from the terminal gas-holder, pump mechanism, mechanism 10 between the piston-rod of the pump and the initial gas-holder, whereby the upward movement of the piston produces an up 15 movement of the initial gas-holder and for causing the initial gas-holder to descend by gravity as the water is discharged beneath the piston and when gas is taken from the distributing gas-holder, the up movement of 20 the initial gas-holder producing a vacuum therein and a suction through the pipe leading from the generator into the initial gas-holder, and the descent of said holder forcing the gas through the pipe leading to the terminal gas-holder.

7. In an apparatus for making gas, the combination of initial and terminal gas-holders, water-tanks in which said holders are fitted and move, a source of gas-supply, a generator, a pipe leading from the source of supply to and into the generator, a valve-controlled air-pipe leading from the external atmosphere to the generator, another valve-controlled pipe leading from the generator into 35 the initial gas-holder, a pipe extending from the initial gas-holder to and into the terminal gas-holder to convey gas to the latter, a distributing-pipe leading from the terminal gas-holder, pump mechanism, mechanism between the piston-rod of the pump and the initial gas-holder for causing an up movement 40 of the initial gas-holder as the piston rises, and means for causing the initial gas-holder to descend by gravity, as the water is discharged beneath the piston and when gas is taken from the distributing gas-holder, the up movement of the initial gas-holder producing a vacuum therein and a suction through the air-pipe leading into the generator and 45 through the pipe leading from the generator to the initial gas-holder, and a descent of said holder forcing the gas through the pipe leading to the terminal gas-holder.

8. In an apparatus for making gas, the combination of initial and terminal gas-holders, water-tanks in which said holders are fitted and move, a source of supply, a generator, a pipe leading from the source of supply to the generator, a valve-controlled air-intake pipe 55 leading from the external atmosphere to and into the generator, and formed or provided at its end within the generator with a perforated discharge, a valve-controlled pipe leading from the generator into the initial gas-holder, a pipe extending from the initial gas-holder to and into the terminal gas-holder, a

distributing-pipe leading from the terminal gas-holder, pump mechanism, mechanism between the piston-rod of the pump and the initial gas-holder, for causing an up movement 70 of the initial gas-holder, and means for causing the initial gas-holder to descend by gravity as the water is discharged beneath the piston and when gas is taken from the distributing gas-holder, the up movement of the 75 initial gas-holder producing a vacuum therein and a suction through the air-intake pipe leading to the generator and through the pipe connecting the generator with the initial gas-holder, and the descent of said holder forcing 80 the gas through the pipe leading to the terminal gas-holder.

9. The combination, in an apparatus for making gas, of initial and terminal gas-holders, water-tanks in which said holders are fitted and move, a fluid-containing storage-tank, a generator, an air-pipe leading to the generator and having an automatically-operated valve, a pipe leading from the storage-tank and extending into the generator, said 90 pipe formed or provided at its end within the generator with a valve-seat, a valve normally against the seat, a pivoted lever provided at one end with a float-ball, and connected at its opposite end to the stem of the valve, a 95 pipe connection between the generator and the initial gas-holder, and means for causing an up movement of the initial gas-holder whereby a suction is created through said pipe connection between the generator and 100 initial gas-holder.

10. In an apparatus for making gas, the combination, of initial and terminal gas-holders, water-tanks in which said holders are fitted and move, a storage or supply tank, a 105 pipe leading therefrom and communicating with the initial gas-holder, and adapted to permit free flow therethrough into the initial gas-holder, a pipe extending from the initial 110 gas-holder to and into the terminal gas-holder, a distributing-pipe leading from the terminal gas-holder, pump mechanism, mechanism between the piston-rod of the pump and the initial gas-holder, a valve-controlled air- 115 inlet leading to the pump-cylinder, a valve-controlled inlet-pipe leading from the cylinder of the pump to the upper portion of the storage-tank, and means for causing an up movement of the initial gas-holder, and for 120 causing the initial gas-holder to descend by gravity as the water is discharged beneath the piston and when gas is taken from the distributing gas-holder, the up movement of the initial gas-holder producing a vacuum 125 therein, and a suction from the source of supply into said holder, and the descent of said holder forcing the gas through the pipe leading to the terminal gas-holder.

11. In an apparatus for making gas, the combination, of a vertically-movable distributing gas-holder, a water-tank in which the

same is inverted, a pipe leading from the gas-holder, a pipe extending through the water-tank and up into the gas-holder, said pipe having its discharge end formed into an elongated cone, and a rod extending downwardly from the top of the gas-holder and into the cone, said rod passing through the top of the gas-holder and having its upper end adjust-

ably secured thereto, its end within the cone being formed or provided with a ball-valve. ¹⁰

In testimony whereof I affix my signature in presence of two witnesses.
